UNITED STATES PATENT OFFICE.

GEORGE B. AMBLER, OF LEOMINSTER, MASSACHUSETTS, ASSIGNOR TO F. A. WHITNEY CARRIAGE COMPANY, OF LEOMINSTER, MASSACHUSETTS, A CORPORATION OF MASSACHUSETTS.

FILLING CONTROL MECHANISM FOR LOOMS.

Application filed February 10, 1922, Serial No. 535,473. Renewed January 28, 1926.

This invention relates to looms and more particularly to that type of loom wherein a length of filling is drawn through the shed from a supply as distinguished from the usual practice wherein the supply of filling is carried through the shed on a shuttle. Such types of looms are particularly adapted for weaving relatively stiff and heavy material such as cane, reed and substitutes therefor. The present invention more particularly relates to improvements for facilitating the control of the supply of filling. My invention will best be understood by reference to the following description of an illustrative embodiment thereof shown by way of example in the accompanying drawing, wherein:

Fig. 1 is a plan view of certain portions of a needle loom adapted particularly for operation on artificial reed commonly known as fiber;

Fig. 2 is an end elevation of certain of the parts shown in Fig. 1;

Fig. 3 is a section on the line 3—3 of Fig. 2; and

Fig. 4 is a section through the adjacent portions of two cooperating wheels of the feeding mechanism along a radial line and is on a large scale.

Referring to the drawings, I have there shown a supply of filling material consisting of a roll 5 of fiber or artificial reed journaled to rotate on a suitable stationary support 7. The end of the filling is supported on one side of the loom frame by the frictional catch 9 and it is seized and a length thereof drawn through the shed by means of the needle 11, the type of loom illustrated by way of example being what is known as a single needle loom.

A large roll of heavy material as 5 offers a considerable and varying resistance to unwinding and is subject to inertia. In accordance with my invention, therefore, I provide means whereby the filling strand is drawn from the roll 5 independently of the action of the needle 11 in such manner that a suitable slack of the filling strand is provided adjacent the holding means 9 as illustrated diagrammatically in Fig. 1 so that the needle 11 acts merely to over-

come the frictional resistance of the holding means 9 and operates under substantially constant conditions in drawing the filling between the warps. For this purpose I preferably provide a feeding means which may be organized as a unit and secured to the side frame 13 of the loom and for this purpose I provide a suitable bracket or frame 15 which provides a bearing for a shaft 17 on one end of which is a gear 19, herein a bevel gear, adapted to mesh with a gear 21 mounted on one of the power driven shafts of the loom. The bevel gear connection, of course, is exemplary of other means for providing a power transmitting connection between one of the driven shafts of the loom and the shaft 17. A suitable end bearing (not shown) may, of course, be provided for the lower end of the shaft 17 when necessary or desired. The shaft 17 is adapted to drive a wheel 23 adapted to act on the filling strand and feed the same. Herein this wheel 23 is loose on the end of the shaft 17, which shaft, however, carries a gear 25 from which the wheel 23 is driven by means of the back gearing 27 supported on the bracket 15.

One or more cooperating idle wheels 29 serve to press the filler strand against the feed wheel 23 and conveniently as shown in Fig. 4 the face of the wheel 23 may be grooved and the faces of the wheels 29 bevelled off to enter this groove, the crests of the bevelled off portions, however, being themselves grooved to fit the filler strand. I herein show two idler wheels 29 which serve to clamp the filler strand at two points and bind it to the feed wheel 23 around an extended arc whereby the feed wheel takes a binding grip on the same. The wheels 29 may be journaled on a lever 31 pivoted to an extension of the bracket 15 to swing in a horizontal plane and having a portion extending as a handle as clearly seen in Fig. 1. A spring 33 secured to the lever and to a suitable attaching member 35 secured to the bracket or auxiliary frame 15 normally swings the wheels into cooperating relation with the feed wheel 23 so that the strand will be fed. Preferably also for a purpose presently to be described the

lever 31 carries a fairleader 37 through which the filling strand is led on its way to the feeding wheels.

It will be apparent from the description that as the motion of the loom proceeds the feed wheel 23 will be continuously driven and will draw off the filling strand from the roll 5 and deliver a supply of slack strand between the roll and the holding device 9. The needle, operating intermittently, draws up a sufficient amount of the filling strand from this slack without any resistance from the heavy roll 5. The speed of the parts is so proportioned that the continuous feed of the strand supplies constantly sufficient slack for the action of the needle. If, however, it is desired to interrupt the feed the lever 21 may be swung counterclockwise viewing Fig. 2, releasing the pressure of the rolls 29 on the feed roll 23. Since the fairleader 37 is mounted on the lever 29, the strand will be lifted out of cooperation with the wheel 23, thus positively stopping the feed. This removal of the strand from the groove in the wheel 23 by the action of the fairleader permits it to be lifted out from between the wheels if desired, in which case the lever may again be released and the feed of the strand will be interrupted although the wheel 23 may still be driven, this being a convenient operation for certain contingencies of adjustment of the loom mechanism.

The two binder wheels 29 tension a considerable length of the strand tensioned around the feed wheel 23 and the strand is thus smoothed out and straightened and delivered in good condition for incorporation into the fabric.

For different widths of fabric a shorter or longer filling strand is required. In the embodiment of the invention shown the wheel 23 may be changed to provide a wheel of sufficient size for the desired purpose. Obviously the arrangement of parts is such that the two binder wheels will cooperate with feed wheels of different sizes.

Having described in detail the particular embodiment of my invention shown by way of example in the accompanying drawing, what I claim as new and desire to secure by Letters Patent I shall express in the following claims:

1. In a loom of the class described wherein a mechanical picking device grasps the end of the filling strand and carries it endwise through the shed, a holding device for clamping the strand to hold the end to be taken by the picking device and arranged to yield to the traction of the latter and driven means continuously acting on the filling to feed it from the supply independently of said picking means and deliver it slackly to the rear of said holding means.

2. In a loom of the class described wherein

a mechanical picking device grasps the end of the filling strand and carries it endwise through the shed, a holding device for presenting the end of the strand for operation of the picking means thereon and means through which the strand passes acting thereon to draw out a length thereof between the supply and the holding device, said means closing on and gripping a considerable length of strand whereby to true the same.

3. In a loom of the class described a filling strand supply, a holding device for presenting the end of the strand for operation of picking means thereon and means interposed between the holder and supply for feeding and conditioning the strand comprising a relatively large, grooved, driven wheel and a pair of cooperating binder wheels pressed toward said driven wheel at spaced points about the circumference thereof.

4. A device for feeding filling strand comprising as a unitary mechanism a frame for mounting on the loom side, a shaft carried thereby having an end provided with a gear adapted to cooperate with a gear on a shaft of the loom, a feed wheel taking motion therefrom and a spring-pressed, movable support on the frame having a binder wheel cooperating with said feed wheel.

5. A device for feeding filling strand comprising as a unitary mechanism a frame for mounting on the loom side, a shaft carried thereby having an end provided with a gear adapted to cooperate with a gear on a shaft of the loom, a feed wheel taking motion therefrom, a spring-pressed, movable support on the frame having a binder wheel cooperating with said feed wheel and a fairleader on said support.

6. A device for feeding filling strand comprising as a unitary mechanism a frame for mounting on the loom side, a shaft carried thereby having an end provided with a gear adapted to cooperate with a gear on a shaft of the loom, a feed wheel loose on the shaft, back gearing driving the wheel from the shaft and a spring-pressed, movable support on the frame having a binder wheel cooperating with said feed wheel.

7. A device for feeding filling strand comprising as a unitary mechanism a frame for mounting on the loom side, a shaft carried thereby having an end provided with a gear adapted to cooperate with a gear on a shaft of the loom, a feed wheel taking motion from the shaft, a movable spring-pressed support on the frame and a pair of binder wheels on the support adapted to press on the feed wheel at spaced points.

8. The weft feeding device as described comprising a feed wheel and a set of binder wheels yieldingly pressed toward the feed wheel, said wheels having edge portions co-

operatively formed to grip the filling between them.

9. The weft feeding device as described comprising a feed wheel and a pair of binder wheels mounted on a swingable lever yieldingly pressed toward said feed wheel, the edges of said wheels being adapted to grip the filling between them.

10. The weft feeding device as described

comprising a feed wheel, a pair of binder 10 wheels mounted on a swingable lever yieldingly pressed toward said feed wheel, the edges of said wheels being adapted to grip the filling between them, and a fairleader for the filling mounted on the lever. 15

In testimony whereof, I have signed my name to this specification.

GEORGE B. AMBLER.
